(57) CLAIM

The ornamental design for a pocket holster, as shown and described.

DESCRIPTION

FIG. 1 is a perspective view of a first embodiment of a pocket holster showing my new design;

FIG. 2 is a rear elevational view thereof;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view thereof shown with a GLOCK ® 43 model handgun in broken lines to illustrate an environment of use; and,

FIG. 9 is a perspective view of the pocket holster of FIG. 1 shown with a GLOCK ® 43 model handgun and pant pocket in broken lines to illustrate an additional environment of use. The broken lines showing the circular eyelet features as well as the “L”-shaped features are included for the purpose of illustrating portions of the article; the broken lines showing a handgun and clothing in FIGS. 8 and 9 are included for the purpose of illustrating environmental structure; the jagged broken lines associated with a bracket are used to show boundaries of the claimed design where no portion(s) of the article within the boundary lines form(s) part of the claim; all broken lines form no part of the claimed design.
